DESIGN FOR A BREAD WRAPPER

Gordon O. Bennett and Carl A. Deisenroth,
Oakland, Calif.

Application February 4, 1939, Serial No. 82,790

Term of patent 14 years

To all whom it may concern:

Be it known that we, Gordon O. Bennett and Carl A. Deisenroth, citizens of the United States, residing at Oakland, in the county of Alameda and State of California, have invented a new, original, and ornamental Design for a Bread Wrapper, of which the following is a specification, reference being had to the accompanying drawing, forming part thereof.

The figure is a plan view of a portion of the bread wrapper embodying our design and showing one complete unit thereof.

We claim:

The ornamental design for a bread wrapper, as shown and described.

GORDON O. BENNETT.
CARL A. DEISENROTH.
